Attorney.

UNITED STATES PATENT OFFICE.

WILLIAM W. COVELL, OF PROVIDENCE, RHODE ISLAND, ASSIGNOR TO
FREDERICK I. MARCY, OF SAME PLACE.

HINGED SHOE-BUTTON.

SPECIFICATION forming part of Letters Patent No. 350,120, dated October 5, 1885.

Application filed July 15, 1885. Serial No. 208,099. (No model.)

To all whom it may concern:

Be it known that I, WILLIAM W. COVELL, a citizen of the United States, residing at Providence, in the county of Providence and State 5 of Rhode Island, have invented a new and useful Improvement in Buttons and Studs; and I do hereby declare the following specification, taken in connection with the accompanying drawings, forming a part of the same, to be a 10 description thereof.

This invention relates to that variety of buttons and studs having a shoe composed of two parts, which are adapted to be turned into a position at right angles to the head of the button or stud, to enable the same to be conveniently applied and removed, and also to be turned into a position parallel with the head, to retain the article in place.

The invention consists in certain features of 20 construction and arrangement hereinafter described and claimed.

In the accompanying drawings, Figure 1 represents a rear view of a sleeve-button embodying the invention. Figs. 2 and 3 show 25 side views of the same at right angles to each other. Fig. 4 represents a vertical section on line $x-x$ of Fig. 3. Figs. 5 and 6 show, respectively, the springs and the shoe parts detached and in perspective. Fig. 7 represents 30 the hollow stem in perspective. Fig. 8 shows a vertical section of the button on line $y-y$ of Fig. 2. Figs. 9 and 10 show side views, at right angles to each other, of a modification of the invention.

35 A is the button-head, which may be of any preferred form or style. To the head A is attached a rearwardly-projecting stem, B, which, as shown in Fig. 7, is hollow, and of a generally rectangular form.

40 C C are springs, each of which is bent upon itself, as shown in Fig. 5, producing two legs, $c-c$. These legs are provided, on those sides which are adjacent to each other when the springs are placed together, with notches or 45 slots c' , (one in each leg,) the said notches forming a slot, as shown in Fig. 8, which constitutes a hinge-bearing for the shoe parts D D. These shoe parts, as particularly shown in Fig. 6, each has a back, d , (preferably semi-circular in shape,) a neck or hinge portion, d' ,

for pivoting the part to the spring C, and, preferably, a wing portion, d'' .

In assembling the parts of the button the shoe parts D D are first placed together so that their neck portions d' d' are in contact 55 and the backs d d in the same plane, and the springs C C are combined with said shoe parts by inserting the portions d' d' of said parts into the slots c' in the sides of the springs. The springs are then inserted into the stem B, and 60 are secured therein and thereto by a pin, E, which is passed through the bends of the springs and perforations b in the stem. As will be readily understood, the springs C keep the shoe parts D constantly pressed together. 65 When the backs d d of the shoe parts D are parallel with the button-head, the wing portions d'' d'' (if the button be in a cuff) will be engaged by the walls of the button-holes, thus preventing the backs from being accidentally 70 turned, and, as shown in Figs. 1 and 4, said wing portions will be in contact with the sides of the stem B and form stops to prevent the backs from swinging any nearer the head. When the backs are turned at right angles to 75 the head, as shown by dotted lines in Figs. 2 and 3, in order that the button may be applied, and force is used to press the backs d through the button-holes, the wings d'' will come in contact with the article to which the button is to 80 be attached and will swing or turn the backs in a position parallel with the head, as will be readily understood. If desired, however, the wing portions d'' d'' may be omitted and the backs be turned from a position at right angles to the button-head by inserting the fingernail between the backs and separating their free edges in a well-known manner. Preferably the backs d d are each provided with upwardly-projecting ribs d'' , and the stem B is 85 furnished with downwardly-projecting spurs b' at its corners, so that when the backs are turned at right angles to the head the ribs will engage the spurs b' and prevent any chance of a lateral movement of said backs on the stem B. 90

In the modification shown in Figs. 9 and 10 the stem B (instead of being in the box form shown in Fig. 7) is in the form of two lugs, and the springs C (instead of being two in number, bent upon themselves to furnish four 95

legs, *c*) are four in number, each the shape of an inverted **L**. These springs have their four legs *c* provided with notches *c'*, the same as hereinbefore described, and are secured in place by two pins, *E*. In this modification the above parts are hinged to the springs in precisely the same way as before set forth, and the action of the button is the same.

What I claim as my invention, and desire to secure by Letters Patent, is—

1. The combination, with the head, of the springs *C*, attached thereto and furnished with side notches or slots, *c'*, and the shoe parts *D*, having hinge portions *d'* passing through said slots or notches and pivoting the said parts to the springs, substantially as set forth.

2. A button or stud having a head, a rearwardly-projecting stem, *B*, springs *C*, secured

to said stem and having side notches or slots, *c'*, and shoe parts *D*, each furnished with hinge portions *d'*, passing through said notches or slots and pivoting said parts to the springs and wing portions *d''*, substantially as set forth.

3. The combination, with the head *A*, having a projecting stem, *B*, furnished with spurs *b'*, of springs *C*, secured to said stem and provided with side notches or slots, *c'*, and shoe parts *D*, each having hinge portions *d'* passing through said notches or slots and pivoting said parts to the springs, and provided with wings *d''* and ribs *d'''*, substantially as set forth.

WILLIAM W. COVELL.
